DESIGN FOR A COMBINATION LOCK

Samuel R. Fraim, Lancaster, Pa.

Application August 8, 1936, Serial No. 64,312

Term of patent 7 years

To all whom it may concern:

Be it known that I, Samuel R. Fraim, a citizen of the United States, residing in School Lane Hills, Lancaster, Lancaster County, Pennsylvania, have invented a new, original, and ornamental Design for a Combination Lock, of which the following is a specification, reference being had to the accompanying drawing, forming part thereof, in which:

Figure 1 is a plan view;
Fig. 2 is a face view, and
Fig. 3 is a side elevational view of the combination lock showing my design.

I claim:
The ornamental design for a combination lock, substantially as shown.

SAMUEL R. FRAIM.
